UNITED STATES PATENT OFFICE.

TERRENCE DUFFY, OF SAN FRANCISCO, CALIFORNIA.

CABLE RAILWAY.

SPECIFICATION forming part of Letters Patent No. 257,674, dated May 9, 1882.

Application filed February 11, 1882. (No model.)

To all whom it may concern:

Be it known that I, TERRENCE DUFFY, of the city and county of San Francisco, State of California, have invented an Improvement in 5 Cable Railways; and I hereby declare the following to be a full, clear, and exact description thereof.

My invention relates to certain improvements in cable railways; and it consists in a device 10 for keeping the grip-slot closed, which will protect the tube or tunnel from foreign substances, and yet not interfere with the passage of the grip; and it consists, also, in cleaning attachments upon the traveling dummy, adapted 15 to run within the slot and upon the road to keep them clear, so that the accumulations will not fall within the underlying tunnel while the dummy is passing and the slot is temporarily opened.

20 The object of my invention is to provide a means for keeping closed the grip-slot, so that dirt, and especially snow, ice, &c., which in cold countries are liable to render impracticable the operation of a cable railway, may not fall down into the tube or tunnel in which the traveling cable and its pulleys are operating. 25 The presence of foreign substances when accumulated is very liable to clog and hinder the mechanism, and for this reason a cable tunnel 30 with an open grip-slot has been considered impracticable in places where there is snow and ice.

Referring to the accompanying drawings, Figure 1 shows a top view of the track, a portion 35 of which is cut away to show the underlying closing-strip. Fig. 2 is a longitudinal vertical section of the track and car, showing the operation of the brush. Fig. 3 is a cross-section of the track. Fig. 4 is a bottom view 40 of the car or dummy.

Let A represent any suitable form or construction of a tube or tunnel in the ground, in which may be supposed the operating-pulleys and traveling cable of a wire-rope railway. In order 45 to grip the traveling cable, and thus connect the dummy or car above with it, a suitable grip passes down from the dummy through this slot, known more definitely as the "grip-slot," has been left open for the unobstructed 50 passage and travel of the grip-shank, and con-

sequently along the whole extent of the road foreign substances can drop through into the tunnel.

Under the slot-irons, which form the slot B, 55 are a number of metal strips, C C, jointed to each other in as short sections as desirable, each piece or section being capable of a side movement without affecting the others, but altogether forming a continuous strip directly 60 under the slot B. Upon one side are guides D, which hold the strips C C in place and prevent them from moving to that side at all. Upon the other side are guides E, which allow the strips C C sufficient play, so that when pushed 65 over they will open the slot by removing entirely from under it. Springs F F, suitably secured, operate upon each section of the strips C C to return it against the guides D, in which position it closes the slot.

Let G represent the dummy carrying a grip, of which the shank is H. Said shank is small enough to pass through the slot B. A suitable start is made upon the line, the grip-shank H extending down within the slot. As it advances it pushes to one side the jointed sections or strips C C, each in succession, and each springs back to its place when relieved and closes the slot behind the passing grip. By making the sections short a very small portion of the slot will be opened at a time. It will be perceived that these closing-strips are under the slot, and therefore the slot forms a basin or channel for foreign substances, which readily fall therein, and if not removed they 85 will be dropped within the tunnel as the grip approaches and the closing-strips move to one side. To provide for this I have the following device:

Upon the forward axle of the dummy is an 90 eccentric, I, around which is a band, i, attached to a jointed rod, J, which extends forward in a suitable guide under the car. It has upon its forward end a frame, N, with a cleaner or brush, K, which is adapted to travel within the grip-slot. Diverging arms L L carry other cleaners, preferably rubber strips l l, which keep clean the slot-irons or top of the rod. Small rollers or wheels M run on top of the slot-irons and reduce the friction. The eccentric gives to the brush a forward throw in addition to its progress by reason of being on the traveling dum-

my, and thus not merely causes it to push the dirt and obstructions, but to sweep them out of the slot.

Instead of a brush I could have a blade or knife, in case of ice being in the slot, and thus cut it out, and the arms L L could carry knives also. These knife attachments would only have to be upon a dummy run over the road in the morning, or whenever necessary, while the brush 10 could be used upon each dummy. The foreign matter is thus swept out of the slot, and none will drop through when the slot is opened.

Having thus described my invention, what I claim as new, and desire to secure by Letters 15 Patent, is—

1. In a cable railway having an underground tunnel or tube in which the cable travels and a grip-slot through which the shank of the grip passes, the jointed sections or strips C C 20 under the grip-slot, and confined in suitable guides to close said slot, and to be moved to one side by the passing grip-shank and to return to position by means of springs F, substantially as described.
2. In a cable railway having an underground tunnel or tube and a grip-slot through which the shank of the grip passes, the combination and arrangement of the jointed strips C C, guides D E, and springs F, substantially as 25 described.
3. In a cable railway having an underground tunnel or tube and a grip-slot, the jointed strips 30

C C, closing the said slot underneath and opening as the grip-shank passes, in combination with a cleaning attachment upon the dummy, 35 said cleaner traveling in the grip-slot in advance of the grip-shank, substantially as and for the purpose herein described.

4. In a cable railway having a tunnel or tube and a grip-slot, the jointed strips C C, arranged, 40 as shown, to close or open the slot around the passing grip-shank, in combination with the cleaning device attached to the dummy, consisting of a cleaner, K, operating within the grip-slot, and the cleaners l l on top, and attached to a frame, N, secured to the throw-rod J, operated by an eccentric, I, upon the forward axle of the dummy, substantially as and for the purpose herein described.

5. In a cable railway, as shown, a cleaning 45 device attached to the dummy in front, consisting of the cleaners K, traveling in the grip-slot, and cleaners l l, passing on top of the road, said cleaners having a forward and return motion in addition to the progress of the dummy 50 by means of the frame N, rod J, strap i, and eccentric I upon the forward axle of the dummy, substantially as herein described.

In witness whereof I have hereunto set my hand.

TERRENCE DUFFY.
